UNITED STATES PATENT OFFICE.

WATSON S. GRAY, OF PHILADELPHIA, PENNSYLVANIA.

DESIGN FOR A TIRE FOR BICYCLES.

SPECIFICATION forming part of Design No. 27,274, dated June 29, 1897.

Application filed December 16, 1896. Serial No. 615,933. Term of patent 14 years.

To all whom it may concern:

Be it known that I, WATSON S. GRAY, a citizen of the United States, and a resident of the city and county of Philadelphia, State of Pennsylvania, have invented and produced a new and original Design for Spring-Tires for Bicycles or other Vehicles, of which the following is a specification.

In the accompanying drawings, forming part of this specification, and in which similar letters of reference indicate similar parts throughout the several views, Figure 1 is a side elevation of a tire-spring of my design for bicycles or other vehicles, and Fig. 2 is a section on the line 2 2 of Fig. 1.

The leading feature of my design consists

in the peculiar form of curves of the spring. The spring is formed of a continuous strip A, bent so as to form a series of equidistant and similar reverse curves B, substantially of the form illustrated.

C indicates a tire, and D a rim, between which the spring is located.

I claim—

The design for a tire-spring for bicycles or other vehicles substantially as herein shown and described.

WATSON S. GRAY.
